(57) **CLAIM**

The ornamental design for a mount for electrical receptacle, as shown and described.

DESCRIPTION

FIG. 1 is a top perspective view of a mount for electrical receptacle showing our new design;

FIG. 2 is a bottom perspective view of the mount for electrical receptacle of FIG. 1;

FIG. 3 is a top plan view of the mount for electrical receptacle of FIG. 1;

FIG. 4 is a bottom plan view of the mount for electrical receptacle of FIG. 1;

FIG. 5 is a left side elevation of the mount for electrical receptacle of FIG. 1;

FIG. 6 is a right side elevation of the mount for electrical receptacle of FIG. 1;

FIG. 7 is a front elevation of the mount for electrical receptacle of FIG. 1;

FIG. 8 is a rear elevation of the mount for electrical receptacle of FIG. 1; and,

FIG. 9 is a perspective view of the mount for electrical receptacle of FIG. 1, shown in an exemplary operating environment.

The broken lines are included for the purpose of illustrating portions of the mount for electrical receptacle, and environmental structure, that form no part of the claimed design.
